No. 197

Thaddaeus Fairbanks' improved Design for a Pedestal,
for a Balance. Patented 22nd Aug. 1848.

Fig. 1

Fig. 2

Des. 197

Thaddeus Fairbanks, St. Johnsbury Vt. Letters
Patent No 197. dated August 30. 1848.

The Schedule referred to in these Letters Patent and
making part of the same.

To all persons to whom these Presents shall come Be it
known that I, Thaddeus Fairbanks of St. Johnsbury in the
County of Caledonia and State of Vermont, have invented a
new and ornamental design, for a pedestal for balances for
weighing articles; and I do hereby declare that the same is fully
represented and described in the following specification and
accompanying drawings.

Of the said drawings Figure 1 denotes a top view of
my improved ornamental pedestal. Figure 2. is a side eleva-
tion of it. Figure 3 a longitudinal and vertical section of it.

Having at considerable expense produced a new de-
sign for a balance pedestal, which when reduced to a practical
form, may be readily taken for a pattern by, and from which
others may be cast or founded, and being desirous of protect-
ing myself so far as legally possible against the piracy of in-
dividuals, who sensible of the reputation of the "Fairbanks
scales" attempt to imitate them in every manner in which
they can do so with impunity. I am compelled to not only
apply for a patent on the scale for which my pedestal is par-
ticularly intended, but for a design patent on the ornamental

Dec. 197

32

form of the said pedestal.

The base of the said pedestal is shaped and has an ornamental bas relief of flowers stems and leaves on its upper surface, as seen in Figures 1 and 2. Above and on this base, four fluted columns a, b, c, d, arise as seen in the drawings, the two middle ones being connected by a cross bar e, from the extremities of which the bearings f, g, of the fulcra of the balance beam project.

What I claim is the ornamental design or shape of the base of the pedestal the same including the bas relief thereof, as represented in the drawings, and in combination therewith, I claim the design or shape of the columns thereof, the said design of said columns consisting in making them with flutes as represented in the drawings.

In testimony whereof I have here-to set my sig
nature this fifteenth day of July A. D. 1848.
